WELL BIT CONSTRUCTION

Alfred C. Catland, Alhambra, Calif.

Application October 13, 1936, Serial No. 105,371

6 Claims. (Cl. 255—71)

This invention relates to well drilling tools and relates more particularly to an improved construction for roller rock bits. A general object of the invention is to provide an improved well bit construction that is extremely simple and that is strong and long wearing.

In roller rock bits for use in the rotary method of well drilling it is very desirable to provide for the transmission of the stresses and forces from the parts receiving the same directly to the body or shank of the tool. In bit structures where the stresses are transmitted from one member to a second member and then from the second member to the shank considerable play and wear develops between the parts due to the essential tolerances in the machine work and poor workmanship.

Another object of this invention is to provide a strong practical bit construction in which the parts that receive the severe operating stresses transmit such stresses directly to the body of the bit.

Another object of this invention is to provide a roller bit construction in which the cutter carrying shafts or pins have their opposite end portions directly bearing on integral parts of the bit body for the direct transmission of the operating forces to the body.

Another object of this invention is to provide a bit construction of the character mentioned in which the inner cutters are partially rotatably supported on the pins and are partially rotatably supported directly on integral parts of the shank.

A further object of the invention is to provide a bit construction of the character mentioned that may be easily and quickly repaired or reconditioned when worn.

The various objects and features of my invention will be fully understood from the following detailed description of a typical preferred form and application of the invention, throughout which description reference is made to the accompanying drawings, in which:

Fig. 1 is a central longitudinal detailed sectional view of a bit embodying the present invention. Fig. 2 is a side elevation of the bit with the lower portion appearing in vertical cross section in a plane normal to the plane of sectioning of Fig. 1, and Fig. 3 is a fragmentary vertical detailed sectional view illustrating the manner in which the bit may be reconditioned.

The bit illustrated in the drawings and embodying the present invention includes, generally, a shank or body 10, two sets of inner roller cutters 11 and 12, means 13 for rotatably supporting the

sets of inner cutters 11 and 12, and outer cutters 14 rotatably mounted on the body 10.

The shank or body 10 is intended to be connected with the lower end of a well drilling string S and is provided to support the cutters and the various other parts of the tool. In the typical structure illustrated in the drawings a tapered screw threaded socket 17 extends into the upper end of the body 10 to receive a threaded pin 18 of a drill collar or similar part on the string S. In accordance with the invention the body 10 is an integral member comprising an upper portion and depending parts or wings. The upper portion of the body 10 may be cylindrical, as illustrated. Two legs or wings 19 project downwardly from the lower end of the body 10 at diametrically opposite points. The particular body 10 illustrated has a downwardly and outwardly flared lower portion 16 and the legs 19 project downwardly from the portion 16. Flat thrust surfaces 20 are provided on the inner sides of the legs 19. The surfaces 20 are inclined downwardly and inwardly. The lower ends 21 of the wings 19 are flat and normal to the surfaces 20.

The integral body 10 further includes legs or wings 22 projecting downwardly and outwardly from the lower body portion 16. The legs 22 are spaced substantially 90° from the wings 19.

Raised thrust surfaces 23 are provided on the inner sides of the wings 22. The surfaces 23 are inclined downwardly and outwardly with respect to the vertical axis of the bit. The lower ends 24 of the wings 22 are flat and substantially normal to the surfaces 23. The four spaced wings 19 and 22 define an open socket-like space at the lower end of the body 10. An integral partition or wall 25 of the body 10 separates this space from the lower end of the socket 17. In accordance with the invention a stud or web 26 depends from the body wall 25. The web 26 is an integral part of the body 10 and lies in or adjacent a central vertical plane of the body. The opposite side edges of the web 26 which oppose the wings 22 are provided with projecting wings 27. The wings 27 are integral with the web 26 and are inclined downwardly and outwardly. Raised thrust surfaces 28 are provided on the outer sides of the wings 27. The surfaces 28 are substantially parallel with the thrust surfaces 23 of the wings 22. The lower ends 29 of the wings 27 are preferably flat and normal to the surfaces 28.

In accordance with the invention the stud or web 26 is characterized by integral bearing parts 30 projecting from its opposite sides toward the wings 19. The bearing parts 30 are cylindrical

and their longitudinal axes are normal to the bearing surfaces 20 of the wings 19. Bosses 31 are provided on the web 26 at the bases or inner ends of the bearing parts 30. The outer ends of the bosses 31 form flat annular thrust surfaces 32. The peripheries of the bosses 31 are preferably chamfered or bevelled, as illustrated. The outer ends of the bearing parts 30 are preferably flat and normal to the longitudinal axis of the parts. It will be noted that the bearing parts 30 and the bosses 31 are integral elements of the shank or body 10.

The cutters 11 are rotatably supported at the lower end of the body 10 to act on the inner portion of the well bore. The inner cutters are provided in sets or pairs each pair including a cutter 11 and a larger cutter 12. The cutters 11 and 12 are roller cutters, the cutters 11 being cylindrical and the cutters 12 being frusto-conical. The cylindrical cutters 11 have central longitudinal openings 34 and peripheral cutting teeth 35. The cutting teeth 35 may be straight and axial as illustrated. In accordance with the invention the inner ends of the teeth 35 project beyond or overhang the inner ends of the cutters 11. The opposite ends of the cutters 11 may be flat and normal to the axis of the cutters. The frusto-conical cutters 12 are provided with central longitudinal openings 36 and peripheral cutting teeth 33. The teeth 33 may be spiralled or may be straight and axial as illustrated. The opposite ends of the cutters 12 are preferably flat and the teeth 33 may extend beyond or overhang the outer ends of the cutters. The cutters 12 are longer and somewhat larger in diameter than the cutters 11. In practice the small ends of the frusto-conical cutters 12 may be larger in effective diameter than the cutters 11.

The means 13 for rotatably supporting the inner cutters 11 and 12 is a feature of the invention. The means 13 provides for the mounting of the cutters 11 and 12 on shafts or pins 37 which are directly carried by integral portions of the body 10. In accordance with the invention a downwardly and outwardly inclined opening 38 is provided in the lower portion of each wing 19 and a correspondingly inclined socket 39 is provided in each bearing part 30. The sockets 39 may extend inwardly through the bosses 31 to have their inner ends in communication. The cutter supporting shafts or pins 37 are passed inwardly through the openings 38 and have their inner end portions threaded in the sockets 39. The threaded inner portions of the pins 37 may be reduced in diameter so that the pins present inwardly facing annular shoulders 40 which bear on suitable surfaces of the bearing parts 30. Heads 41 are provided on the outer ends of the pins 37 and fit suitable recesses or sockets 42 in the outer sides of the wings 19. The heads 41 may be socketed to facilitate the threading and unthreading of the pins 37. Edge portions 43 of the pin heads 41 may be peened over into notches 44 in the outer sides of the wings 19 to prevent unthreading of the pins 37. When the pins 37 are properly threaded in place they serve to tie the wings 19 to the web 26, thus strengthening the bit assembly.

The pins 37 pass through the longitudinal openings 34 of the cutters 11 and the longitudinal openings 36 of the cutters 12 to rotatably support the cutters. In accordance with the invention the inner portions of the cutters 11 fit around and rotatably bear on the bearing parts 30 while anti-friction rollers 45 or other suitable means

rotatably support the outer portions of the cutters 11 on the pins 37. Thus the cutters 11 are rotatably supported on both the integral bearing parts 30 of the body 10 and the pins 37 which are directly carried by the body. The projecting inner portions of the teeth 35 overhang the bosses 31. The inner surfaces of the overhanging teeth 35 may be bevelled to have suitable clearance with the bosses 31. The teeth 35 overhanging the bosses 31 project inwardly to immediately adjacent the center of the bit at the lower end of the web 26 to act on the innermost portion of the well bore and to prevent contact of the web 26 with the earth formation. The inner ends of the cutters 11 may bear on the thrust surfaces 32 of the bosses 31.

The frusto-conical inner cutters 12 are rotatably supported on the pins 37 through rollers 46 or other equivalent anti-friction bearing means. Thrust washers 47 may be arranged in the inner ends of the cutters 12 to separate the rollers 45 and 46 and to receive end thrusts from the cutters 11. The cutters 12 are arranged with their small ends facing inwardly so that the cutters 11 and 12 act on a tapered mound on the bottom wall of the well bore. As the inner ends of the tapered cutters 12 are larger in diameter than the cutters 11 this mound on the bottom wall of the well bore is stepped so that the cutters on the mound are effective in centralizing and stabilizing the bit. Non-rotatable thrust washers 48 are interposed between the outer ends of the cutters 12 and the thrust surfaces 20 of the wings 19. Tongues or lugs 49 project from the washers 48 and cooperate with the flat ends 21 of the wings 19 to hold the washers against rotation.

The outer cutters 14 are frusto-conical roller cutters. The cutters 14 are provided with central longitudinal openings 52 and may have flat opposite ends as illustrated. Cutting teeth 53 are provided on the peripheries of the cutters 14. The teeth 53 may be straight or spiralled, as desired. The outer corners of the teeth 53 are preferably bevelled off while the inner ends of the teeth may slightly overhang the inner ends of the cutters.

The cutters 14 are rotatably mounted between the wings 22 and 27 to act on the outer portion of the well bore and to cut the bore to gauge. The means for rotatably supporting the cutters 14 includes bushings 54 arranged longitudinally through the cutters 14. The bushings 54 are positioned between the adjacent opposing wings 22 and 27 to have their longitudinal axes inclined downwardly and inwardly to be normal to the surfaces 23 and 28. Pins 63 carry the bushings 54. The pins 63 are passed outwardly through downwardly and inwardly inclined openings 64 in the wings 27 and are threaded into correspondingly inclined openings 65 in the wings 22. The outer ends of the pins 63 may be peened into notches 66 in the wings 22 to prevent unthreading of the pins. Suitable rollers 55 or other anti-friction bearing means may rotatably support the cutters 14 on the bushings 54. The cutters 14 are arranged with their large ends outermost and are rotatably supported on the inclined bushings 54 so that the bevelled off outer ends of their teeth 53 are substantially vertical as they come into engagement with the earth formation. Thrust flanges 56 are provided on the inner ends of the bushings 54 to bear against the surfaces 28. The flanges 56 space the inner ends of the cutters 14 from the wings 27. Lugs 57 project from the flanges 56 and cooperate with

the ends 29 of the wings 27 to hold the bushings 54 against rotation and to assist in transmitting upward thrusts to the wings. Thrust washers 58 are arranged on reduced outer end portions of the bushings 54 to space the cutters 14 from the wings 22 and to transmit the end thrusts from the cutters to the wings. The washers 58 may be pressed or force-fitted on the bushings 54 to facilitate the handling and transporting of the cutter assemblies. Lugs 59 are provided on the washers 58 and cooperate with the ends 24 of the wings 22 to prevent rotation of the washers. The lower ends of the washers 58 and the outer surfaces of their lugs 59 may be bevelled off substantially flush with the outer surfaces of the wings 22.

The invention provides means for flushing the cutters 11 and 12 and the cutters 14. Ports 60 are provided in the body wall 25 to conduct the circulation fluid downwardly from the socket 17 to the spaces which house the pairs of cutters 11 and 12. The circulation fluid is discharged downwardly from the ports 60 to impinge against the cutters 11 and 12. Similar ports 61 are provided in the body wall 25 to communicate with the lower end of the socket 17. The ports 61 discharge the circulation fluid downwardly against the upper parts of the cutters 14.

In accordance with the invention the bit may be easily and inexpensively reconditioned when worn. In the event that the lower portion of the web 26 carrying the bearing parts 30 becomes worn it may be machined off to a flat surface 70 as illustrated in Fig. 3. This will, of course, remove the wings 27 as well as the bearing parts 30 and the bosses 31. A replacement part or element 71 is then integrally joined with the body 10 to replace the portions machined off. The replacement element 71 has a flat upper end 72 to bear against the surface 70. The element 71 is integrally joined with the body 10 by welding 73. The replacement element 71 is identical with the lower portion of the web 26 as originally constructed, that is, it has wings identical with the wings 27 and has bearing parts 30 and bosses 45 31 identical with the above-described bearing parts and bosses. When any other parts of the bit that may have been worn have been replaced or reconditioned the bit provided with the replacement element 71 may be reassembled and again operated.

In operation the bit is connected with the lower end of the rotary well drilling strings and is operated in the well bore in the usual manner. The outer cutters 14 act on the outer portion of the well bore to cut the bore to gauge and to make an annular cut at the bottom of the bore. The inner cutters 11 and 12 act on the inner part of the well bore and form a mound of earth formation on the bottom wall of the bore. As described above, this mound is stepped and the cutters 11 and 12 acting on the stepped conical mound of earth formation materially assist in guiding and centralizing the bit. It will be observed that the several cutters 11, 12 and 14 are rotatably supported by shafts or pins 37 which are directly carried by the body 10. The inner cutters 12 and the outer portions of the cutters 11 are rotatably supported by the pins 37 which have their opposite end parts directly carried by integral elements of the body 10. This mounting of the cutters prevents the development of undesirable play and clearance between the bit parts. The cutters 11 have their inner portions rotatably bearing on the integral bearing parts

30 of the shank. The shafts or pins 37 in addition to supporting the cutters 11 and 12 serve to tie the wings 19 to the integral web 26 of the body, thus strengthening and reinforcing the bit. The parts are assembled so that they may be easily and quickly replaced when worn.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. In a roller bit, a body, a wing depending from the body, a web depending from the center of the body, the wing and web being integral with the body, an integral bearing part on the web, the wing having an opening, the web having an opening concentric with the bearing part, a pin extending between the wing and web and having its end portions directly supported in said openings, a cutter rotatably supported on the outer portion of the pin, and a cutter whose inner portion rotatably bears on said bearing part and whose outer portion is rotatably supported by the pin.

2. In a roller bit, a body, a wing depending from the body, a web depending from the body, the wing and web being integral with the body, an integral bearing part on the web, the wing and said bearing part having openings, a pin passed inwardly through the opening in the wing and threaded in the opening in the bearing part, a head on the pin cooperating with the wing, a cutter partially rotatably supported on the bearing part and partially rotatably supported on the pin, and a second cutter rotatably supported on the pin between the wing and the first mentioned cutter.

3. A roller bit including, a body having depending wings at its periphery, a web depending from the center of the body between the wings, the wings and web being integral with the body, pins projecting upwardly and inwardly from the wings, a single element integrally joined to the web by welding, bearing parts on said element facing the wings and having threaded openings threadedly receiving the inner portions of the pins, and roller cutters partially bearing on said parts and partially bearing on the pins.

4. A roller bit including, a body, wings projecting from the lower end of the body, a web projecting downwardly between the wings, the wings and web being integral with the body, parts on the web projecting toward the legs, the wings and web having inclined openings, the openings in the web extending through said parts, pins passed through the openings in the wings and threaded in the openings in the web to be directly carried by the wings and web, heads on the pins cooperating with the wings whereby the pins tie together the wings and web, and roller cutters rotatable on the pins and overhanging the said parts of the web in which the pins are carried.

5. In a roller bit, a body, a wing depending from the body and having an opening, a web depending from the body, the wing and web being integral with the body, an integral bearing part on the web having a threaded opening, a pin extending between the wing and web and having its inner end directly threaded into the opening in said bearing part and having its outer end supported in the opening in the wing, and a

cutter whose inner portion rotatably bears on said bearing part and whose outer portion is rotatably supported by the pin.

5. 6. In a roller bit, a body, wings depending from the body, a central web depending from the body, the wings and web being integral with the body, integral bearing parts on the web facing the wings, the wings and said bearing parts having openings, the openings in the bearing parts being

threaded, pins passed upwardly and inwardly through the openings in the wings and threaded in the openings in the bearing parts, and roller cutters partially rotatably supported by the bearing parts and partially rotatably supported by the pins, the peripheries of the cutters below the web being in close proximity to protect the web.

ALFRED C. CATLAND.
